UNITED STATES PATENT OFFICE.

LE ROY E. JOLLS, OF DETROIT, MICHIGAN, ASSIGNOR, BY MESNE ASSIGNMENTS, TO
GLEASON WORKS, OF ROCHESTER, NEW YORK, A CORPORATION OF NEW YORK.

DRESSING DEVICE FOR GEAR-GRINDING MACHINES.

Application filed August 2, 1923. Serial No. 655,247.

My invention relates to a dressing device for gear grinding machines, more particularly for machines adapted to the grinding of gears having lengthwise curved or spiral teeth, and it has for its object to provide a simple and practicable device that enables maintaining the grinding member in proper form for accurately grinding the tooth profiles, preferably according to the involute system of generation.

To these and other ends, the invention consists in various features and combinations of parts, all as will appear clearly from the following description, when read in conjunction with the accompanying drawings, the novel features being pointed out in the claims following the description.

In the drawings:

Figure 1 is a plan view of a machine for grinding bevel gears, embodying one arrangement of my invention;

Figure 2 is an end elevation, looking at the edge of the grinding member;

Figure 3 is a sectional view on line 8—8 of Figure 2;

Figure 4 is a similar view showing the dressing device in reversed position, and

Figure 5 is a sectional view on line 10—10 of Figure 2.

The invention is herein disclosed as applied to a bevel gear generating machine of the general type illustrated in Patents Nos. 1,203,608, November 7, 1916, and No. 1,349,951, August 17, 1920, and the mechanism for imparting the necessary indexing and generating movement to the gear blank, in proper relationship to the movement of the grinding member, form no part of this invention and may be of the form disclosed in said prior patents, so that a description of such mechanism is not deemed necessary in the present application.

1 designates the gear blank mounted on a suitable blank support or spindle, while 2 designates the grinding member which is of annular face mill form to cooperate properly with circularly or otherwise curved teeth on a gear.

The grinding member, which is formed of any suitable abrasive material, is of an annular face mill type for cooperation with lengthwise curved gear teeth, the annular portion being of V-shaped cross-section and arranged to pass through a space between

adjacent teeth and cooperate with either one or both adjacent teeth faces. The grinding member is dressed on both inclined faces and on its edge as often as required, and the mechanism for performing the dressing operations on the grinding member will now be described.

Referring to Figures 1, 2, 3, and 4, 20 designates a reversible and oscillatory carrier for the dressing devices, preferably of cylindrical form and mounted within a stationary support or barrel 21. Arranged in the carrier 20, at an angle to its axis of turning movement, is a holder 22 which carries a dressing device 23. The holder 22 is actuated by an operating member in the form of a screw 24, operated by a handle 25, and engaging a hollow threaded portion of the holder 22, so that by turning the handle 25, the holder 22 and the dressing device 23 are moved longitudinally, causing the dressing device 23 to traverse an operating face of the grinding member while the latter is rotated. To dress the oppositely inclined face of the grinding member, the carrier 20 is turned half way around in the support 21, moving it from the position shown in Figure 3 to that shown in Figure 4, and thus reversing the position and angle of the dressing device.

The opposite inclined faces of the grinding member are at slightly different angles to the edge of the grinding member, and in order to provide for this variation, the axis of turning of the carrier 20 is arranged at an angle to the rotary axis of the grinding member, corresponding to the difference in the angle of inclination between the opposite inclined faces of the grinding member, so that when the dressing device 23 is reversed, it will cooperate properly with the corresponding opposite faces of the grinding member.

The reversible carrier 20 is held in its position of adjustment by a spring-controlled locking bolt 26, Figure 5 actuated inwardly by a spring 27 and cooperating with one of the openings or sockets 28 in the carrier. To change the position of the carrier, the locking pin 26 is withdrawn by the head 29, to permit turning of the carrier to its opposite position. 30 is a stationary holder in the carrier 20, provided with a dressing device 31 arranged for co-

operation with the outer edge 32 of the grinding member. To dress such outer edge, the carrier 20 is oscillated back and forth, to move the dressing device 31 across the surface 32, and to dress one of the inclined faces of the grinding member, the carrier 20 is brought to proper position and then locked, after which the handle 25 is operated to move the holder 22 and the dressing device 23 endwise and into engagement with the corresponding inclined face of the grinding member. The support 21 is carried on a standard 35, see Figure 2, having an angular extension 36 pivoted at 27, and held in operating position by an attaching nut 38.

While the invention has been described with reference to a particular arrangement, it is not limited to the specific construction set forth, and this application is intended to cover any modifications or departures coming within the novel features of the improvement or the scope of the following claims.

25 I claim:

1. In a gear grinding machine comprising an annular grinding member of V-shaped cross-section, a dressing device movable into engagement with one of the inclined operative faces of the annular grinding member, a holder for the dressing device, a rotatable carrier in which the holder is movable endwise, the holder being movable from one end of the carrier parallel to one of the inclined faces of the grinding member, and an actuating member located at the opposite end of the carrier and having threaded engagement with the holder to move the dressing device back and forth over an inclined face of the grinding member.

2. In a gear grinding machine comprising an annular grinding member of V-shaped cross-section, a dressing device movable selectively into engagement with either of the inclined operative faces of said grinding member, a holder for the dressing device, a cylindrical support, a cylindrical carrier rotatably mounted in said support, the aforesaid holder being endwise movable from one end of the carrier parallel to one of the inclined faces of the grinding member, and an actuating member at the opposite end of the carrier having threaded engagement with the holder to move the dressing device back and forth across said inclined face of the grinding member.

operative engagement with said holder to move the latter.

3. In a gear grinding machine comprising an annular grinding member of V-shaped cross-section, a cylindrical support, a cylindrical carrier mounted in the support, a dressing device holder movable endwise of the carrier at an angle to its longitudinal axis, the carrier being rotatable to permit cooperation of said dressing device with either inclined operative face of the grinder, and a second dressing device holder fixedly mounted in the carrier for cooperation with the edge of the grinding member, the carrier having an oscillatory movement to bring the latter dressing device holder into cooperative relation with the edge of the grinding member.

4. In a gear grinding machine comprising an annular grinding member of V-shaped cross-section, a dressing device movable selectively into engagement with either of the inclined operative faces of said grinding member, a holder for the dressing device, a cylindrical support, a cylindrical carrier rotatably mounted in said support, the aforesaid holder being endwise movable of the carrier and mounted at an angle to the longitudinal axis of the carrier whereby rotating of the carrier permits the dressing device to move parallel to either respectively of said inclined surfaces of the grinding member, and an actuating member having operative engagement with said holder to move the latter, the reversing axis of the carrier being at an angle to the rotary axis of the grinding member.

5. In a gear grinding machine comprising an annular grinding member of V-shaped cross-section, a dressing device movable selectively into engagement with either of the inclined operative faces of the grinding member, a holder for the dressing device, a cylindrical support, a cylindrical carrier that is rotatable in the cylindrical support, said holder being endwise movable from one end of the carrier parallel to one of the inclined faces of the grinding member, and an actuating member at the opposite end of the carrier having threaded engagement with the holder to move the dressing device back and forth across said inclined face of the grinding member.

In witness whereof, I have hereunto signed my name.

LE ROY E. JOLLS.
